UNITED STATES PATENT OFFICE.

MARVIN SMITHY, OF LAWRENCEVILLE, VIRGINIA.

METER.

1,314,285.

Specification of Letters Patent. Patented Aug. 26, 1919.

Application filed June 18, 1916. Serial No. 104,047.

To all whom it may concern:

Be it known that I, MARVIN SMITHY, a citizen of the United States, and a resident of Lawrenceville, in the county of Brunswick and State of Virginia, have invented a certain new and useful Improvement in Meters, of which the following is a specification.

My invention relates to improvements in meters, and it consists in the combinations, constructions, and arrangements herein described and claimed.

An object of my invention is to provide a novel form of meter to be used with an automobile or other similar vehicle for the purpose of keeping track of the mileage of tires or other similar parts of the vehicle, there being an odometer or registering device for each of these individual features.

20 A further object of my invention is to provide a meter which is capable of having any one of its several odometers released from the driving mechanism and reset at will.

25 A further object of my invention is to provide a plurality of odometers driven simultaneously and a movable device for engaging each of the odometers to throw the latter out of operative position and also to 30 reset it.

A further object of my invention is to provide a novel form of speedometer, which may be used in connection with the odometers.

35 Other objects and advantages will appear in the following specification, and the novel features of the invention will be particularly pointed out in the appended claims.

My invention is illustrated in the accompanying drawings forming part of this application, in which—

Figure 1 is a face view of the meter.

Fig. 2 is a horizontal section along the line 2—2 of Fig. 7.

45 Fig. 3 is a section along the line 3—3 of Fig. 2.

Fig. 4 is a section on the line 4—4 of Fig. 5.

Fig. 5 is a section on the line 5—5 of Fig. 1.

Fig. 6 is a detailed sectional view of one 50 of the odometers.

Fig. 7 is a side view partially broken away of the meter.

Fig. 8 is a top plan view of a modified form of meter with the setting ring removed.

55 Fig. 9 is a bottom plan view of the setting ring.

Fig. 10 is a detailed section on line 10—10 of Fig. 4.

Fig. 11 is a perspective view of the centrifugal actuating device for the speed- 60

ometer.

In carrying out my invention I provide a casing 1 which is cylindrical in shape. Disposed at the rear of the casing is a centrifugal device consisting of a shaft 2 which is 65 mounted to rotate in bearings 3. Disposed at substantially the center of the shaft is a centrifugal wheel 4. As will be seen from Fig. 2, this wheel is pivotally mounted at 4°, so that it may turn from the dotted line 70 position shown in Fig. 2 to the full line position or vice versa.

The shaft 2 is provided with an enlarged portion, 2'. Surrounding the shaft 2 on one side of the portion 2' is a spiral spring 5, 75 which bears at one end on a slidable collar 6, the other end bearing on the portion 2'. On the opposite side of the portion 2' is a similar spring 7, which bears at one end of the portion 2', and on the opposite end on a 80 slidable collar 8. I desire to call particular attention to the construction of these springs. It will be observed that they are made heavy in the central portion and lighter toward their ends. 85

The wheel 4 is connected with the slidable collar 6 by means of a link 9, which is pivotally connected to the wheel at 9' in a slot 9'. The slidable collar 8 is connected to the opposite side of the wheel by a link 10, which 90 is pivotally secured at 10' in a slot 10'.

The collar 6 is provided with a groove 11 arranged to receive the spherical end 12' of a pivoted arm 12. The opposite end of this arm is formed in the shape of a segmental 95 gear 13, which meshes with a pinion 14 on a shaft 15. The shaft 1', as will be seen from Fig. 1, bears an arm or pointer 16, which plays over a dial 17 indicating miles per hour. 100

The speedometer arrangement thus far described operates in the following manner. Normally, when the vehicle is at rest, the position of the parts is that shown in Fig. 2. When the shaft 2 is turned by means of flexible transmission mechanism 18 extending from the running parts of the vehicle to the shaft 2, see Fig. 11, the centrifugal force of rotation tends to move the wheel 4 from the full line position to the dotted line position, 110 this movement being resisted by the spiral springs 5 and 7, since the movement of the

wheel 4 tends to also move the collars 6 and 8, and therefore to compress these springs.

By making the springs larger and heavier in the center, the movement of the collar 6 may be such that its displacement will be in proportion to the speed of the vehicle, because it will be observed that the farther the spring is compressed, the greater resistance to compression will take place. It is a matter of experiment to determine the relative sizes and strengths of the end convolutions of the springs, as compared with their central convolutions, so that the movement of the collar 6 will be in exact proportion to the speed of the vehicle.

The means for measuring the mileages which are obtained by the various parts of the vehicle such as the tires, includes the shaft 2, at the end of which is a bevel gear 19, see Figs. 11 and 5. This meshes with a gear 20, on a shaft 21, bearing a gear 22, see Fig. 4, which is in mesh with a gear 23, that engages a gear 24 on a shaft 25, having a gear 26, engaging a pinion 27 on a sleeve 28. The latter bears a gear 29 engaging a pinion 30 on a shaft 31, upon which is a gear 32 meshing with a gear 33 on a shaft 34. This shaft extends through a partition 35, and bears at its end, a bevel gear 36. This bevel gear 36 is in mesh with two bevel gears 37 and 37', respectively, the former being on a common shaft with a bevel gear 39, which meshes with a bevel gear 40 on a shaft 41. The latter shaft bears worms 42 arranged to mesh with worm wheels 43, one of which is carried by each odometer 44. That portion of the apparatus including the members 20 to 33, inclusive, constitute a gear train for reducing the speed. The parts including those from 37 to 44 are duplicated on the opposite side of the bevel gear 36, the members 37' to 44' inclusive corresponding to the parts having the same numerals on the opposite sides.

As will be observed from Fig. 6, each of the odometers is provided with a shaft like that shown at 45 in Fig. 6. This shaft bears a bevel gear 46. Each odometer is pivotally mounted at 47 and is held by a spring 48 in such position that its worm wheel 43 or 43' as the case may be, will be normally in engagement with its worm 42 or 42'.

As will be seen from Fig. 4, the shafts 45 of the odometers project through the casing 1. The upper part of the casing 1 is provided with an inwardly extending annular flange 1^x, which supports a setting ring 50, like that shown in Fig. 9. This setting ring bears a thumb wheel 51 on a shaft 52, which is journaled in a sleeve 53, see Fig. 5, carried by the ring 50, a spring 54 tending to hold the thumb wheel 51 normally in an upper position shown in dotted lines in Fig. 5. The opposite end of the shaft 52 is provided with a bevel gear 55, which is

arranged to engage any of the bevel gears 46, carried by the shafts 45 of the various odometers.

In order to permit the gear 55 to be moved in the position, the flange 1^x is slotted, as shown at 1^y. The ring 50 rotates on the flange 1^x as a bearing, and carries with it the shaft 52.

Secured to the flange 1^x is a plate 57 which bears legends 58, such as extra tire No. 1, extra tire 2, and a reading opening 59 through which the odometers may be observed. A glass plate 60 is also carried by the plate 57.

From the foregoing description of the various parts of the meter mechanism, the operation thereof may be readily understood.

Normally, the odometers are all engaged by the driving mechanism, and are driven simultaneously. If now it is desired to record the mileage of a newly replaced tire, the odometer corresponding to the tire is disengaged and reset by moving the thumb wheel 51 around until it is opposite the odometer, then pressing inwardly to bring the bevel gear 55 into registration with the bevel gear 46, see Fig. 5. The inward movement of the gear 55 will cause the opposite end of the pivoted shaft 45 to lift the worm 43 away from the worm 42, thus disengaging the odometer from its driving mechanism. Now, by turning the wheel 51, the wheel 45 may be turned, and the odometer wheels reset. It may here be stated that the specific construction of the odometer forms no part of the present invention, and any form in which the turning of its shaft will reset the number wheels may be used. If it is desired to temporarily put the odometer out of operative relation with its driving mechanism, then the end of the shaft 45 may be secured by means of a hook, such as that shown at 61 in Fig. 7.

In Figs. 1 and 4 I have shown a meter having six (6) odometers, while in Fig. 8 I have shown a modified form in which eight (8) odometers are used, otherwise the devices are identical.

I claim:

1. In a meter, the combination with a casing, a plurality of odometers disposed within the casing, a driving means common to all of said odometers, and means carried by said casing and shiftable thereon to any odometer position for disengaging any of said odometers individually from said common driving mechanism.

2. In a meter, the combination with a casing, a plurality of odometers disposed within the casing, a driving means common to all of said odometers, and means carried by said casing and shiftable thereon to any odometer position for disengaging any of said odometers individually from said com-

115

120

125

130

mon driving mechanism and for resetting the odometer thus disengaged.

3. In a meter, the combination of a plurality of odometers, a driving means common to all of said odometers, a casing, a movable member supported by the casing and means carried by said movable member and shiftable therewith from one odometer position to another for disengaging any of said odometers from said common driving means.

4. In a meter, the combination with a casing, of a plurality of odometers carried therein, a driving mechanism common to all the odometers, a rotatable ring carried by the casing, a resetting wheel carried by said ring and arranged to be brought into operative position with respect to any of the odometers, and means connected with said wheel arranged to be brought into engagement with a portion of the odometer for releasing the odometer from the common driving mechanism.

5. In a meter, the combination with a casing, of a plurality of odometers carried therein, a driving mechanism common to all the odometers, a rotatable ring carried by the casing, a resetting wheel carried by said ring and arranged to be brought into operative position with respect to any of the odometers, and means connected with said wheel arranged to be brought into engagement with a portion of the odometer for releasing the odometer from the common driving mechanism, and for resetting the odometer.

6. In a meter, the combination of a plurality of odometers; a driving means common to all of said odometers, a casing, a rotatable member carried by the casing and means carried by the rotatable member and shiftable therewith from one odometer position to another for disengaging any of the said odometers from said common driving means.

7. In a meter, the combination of a plurality of odometers, a driving means common to all of said odometers, a casing, a rotatable member carried by the casing, and means carried by the rotatable member and shiftable therewith from one odometer posi-

tion to another for disengaging any of the said odometers from said common driving means, and for resetting said disengaged odometer at will.

55

8. In a meter, the combination of a plurality of odometers, a driving means common to all of said odometers, and a unitary mechanism shiftable from one odometer position to another, and adapted to disengage said odometers individually from said common driving mechanism.

9. In a meter, the combination of a plurality of odometers, a driving means common to all of said odometers, and a unitary mechanism shiftable from one odometer position to another and adapted to reset said odometers individually.

10. In a meter, the combination of a plurality of odometers, a driving means common to all of said odometers, and a single instrumentality shiftable from one odometer position to another and adapted to be placed in operative relation with each of said odometers, said instrumentality having means for disengaging said odometers from said driving means and for resetting said odometers.

70

11. In a meter, the combination of a plurality of odometers, a driving means common to all of said odometers, a casing, a rotatable ring carried by the casing, and means carried by the ring and shiftable therewith from one odometer position to another for disengaging any of said odometers from said common driving means.

80

12. In a meter, the combination of a plurality of odometers, a driving means common to all of said odometers, a casing, a ring rotatable on said casing, and means carried by said ring and movable from one odometer position to another for resetting any of said odometers.

90

13. In a meter, the combination of a plurality of odometers, a driving means common to all of said odometers, a casing, a ring, rotatable on said casing, and means carried by the ring and shiftable from one odometer position to another for disengaging any of said odometers and for resetting said disengaged odometer at will.
